UNITED STATES PATENT OFFICE.

GERARD JOHAN LUGT, OF AMSTERDAM, NETHERLANDS, ASSIGNOR TO NAAMLOZE VENNOOTSCHAP NEDERLANDSCHE FABRIEK VAN WERKTUIGEN EN SPOORWEG-MATERIEEL GENAAMD "WERKSPOR," OF AMSTERDAM, NETHERLANDS, A DUTCH COMPANY.

CONSTRUCTION AND MOUNTING OF THE CYLINDER OF A DOUBLE-ACTING TWO-STROKE MOTOR.

Application filed January 17, 1925, Serial No. 2,973, and in the Netherlands March 8, 1924.

My invention relates to double-acting two-stroke internal combustion engines.

A double-acting two-stroke engine should fulfill, inter alia, the following conditions:

(1) The cylinder barrel should have freedom of expansion;

(2) Tensile stresses in the material of the cylinder barrel should be avoided, especially when said barrel is weakened by the presence of scavenging and outlet ports;

(3) Distortion of the cylinder barrel owing to the considerable difference between the temperatures of the part containing the outlet ports and of the opposed part containing the scavenging ports should be avoided;

(4) Expansion of the cylinder barrel should not affect the adjustment of the valve mechanism;

(5) The intermediate central part of the barrel, i. e. that portion, which contains the outlet and the scavenging ports should be easily removable.

The cylinder construction embodying the present invention fully meets these conditions.

The annexed more or less diagrammatic drawing illustrates one embodiment of the invention, my principle of which can only be clearly explained by a detailed description of said embodiment in the drawing.

Fig. 1 is a diagrammatic side elevation of a double acting vertical two-stroke engine embodying the invention;

Fig. 2 is a vertical central section through one of the engine cylinders, drawn to an enlarged scale;

Fig. 3 shows in section means for sealing the joint between adjacent parts of the cylinder barrel;

Fig. 4 is a diagram of the water circulation of the outlet ports.

The body of the engine is composed of three main parts: a bed plate with crank case 1, and two cylinder jackets 2 and 3. Secured to the jacket 2 by means of bolts 5 (Fig. 2) is the bottom cylinder cover 4, and secured to the jacket 3 by means of bolts 6 is a cap 8, which serves to clamp the cover 10 and a ring 9 on the top edge of the upper cylinder barrel part. The jackets 2 and 3 are spaced apart by hollow columns 11 and

are supported through hollow columns 12 by the crank case 1, the long bolts shown as extending from the top of jacket 3 to the bottom face of the bed plate serving to hold said parts together.

The end parts 13 and 14 of the cylinder barrel are free to axially expand upwardly and downwardly within their jackets 2 and 3, respectively. The sealing of the joints between the said barrel parts and their jackets does not offer any special difficulty. Mounted intermediate the jackets 2 and 3 is an individually water jacketed annular piece 17 provided with scavenging air ports 18 and with outlet ports 19. The part 17 has both in its upper and in its bottom face a circular groove (Fig. 3) to receive centering collars 15 and 16 of the end barrel parts 14 and 13, a small clearance 20 between the collar and the bottom of the groove allowing of free axial expansion both of the end parts 13, 14 and of the central annular part 17. The latter comprises two halves axially joined together as at 21, so that the strains in the exhaust half of the annulus which is heated to a higher temperature than the other half containing the scavenging air ports, cannot appreciably exceed those in said other half. Moreover, a part composed of two halves is easy to handle, which is of special importance, since the barrel part containing the scavenging air ports and the outlet ports is subjected to the heaviest wear and tear and should, therefore, be easy of removal. In many cases it will suffice to plane the flanges forming the joints 21 and to turn the halves to the original cylinder diameter.

To avoid leakage through the joint 20 and the circular groove, I preferably use the construction illustrated in Fig. 3. Encircling the centering collar 15, which slidably fits the circular groove of part 17, is a ring 22 of suitable packing material, said ring being clamped in position by a toroidal rubber tube 23 through which circulates water under pressure entering and leaving through pipes 24. This hydraulic pressure on the packing ring 22 ensures a perfect sealing of the joint, while the cooling effect of the circulating water safeguards the packing material and the rubber tube against deterioration by the heat of the cylinder. If desired, the rubber

tube may be coated with an insulating material, for instance, asbestos fabric.

The upper barrel part 14 is closed by the water cooled ring 9 and the cover 10, which latter accommodates the valves.

The bottom cylinder cover 4 is provided with a combustion chamber 25, having, inter alia, a scavenging air valve 26 for expelling the combustion gases from the combustion chamber 25 which, as will be seen, cannot be readily sufficiently washed by the air entering through the ports 18.

Fig. 4 is a diagrammatic illustration of the water cooling arrangement for the exhaust half of part 17. As shown, the bars between the exhaust ports are provided with passages 27 for the circulation of cooling water. In order that choking up of a passage or breakage of a bar may immediately manifest itself, the ring is so formed that the water flows successively through the various passages 27 as indicated by arrows.

As will be perceived an important feature of the invention is, that the cylinder barrel 25 is composed of three separate parts, the outer parts being secured with their ends to the frame and to the central part, containing scavenging and exhaust ports, and being provided on both sides with an expansion joint between the cylinder space and the atmosphere. The lower part of the cylinder barrel can, indeed, be said to be secured to the frame by means of its cover. It is of importance that the cylinder ends be secured as rigidly as possible. With such an arrangement, the whole interior wall of the cylinder can freely expand without impairing the correct guiding of the piston.

Another feature of the invention is, that each barrel portion has its individual water jacket.

Still another feature of the invention is, that the intermediate central part is divided in such a manner that the exhaust ports and the scavenging air ports are provided in separate parts thereof, for in this case expansion by heat is not capable of causing dangerous stresses. This division of the intermediate central part allows of opening the cylinder without even touching the distributing gear, provided, of course, that the frame has the required openings. When the intermediate central part has been re-

moved, the cylinder and the piston can be inspected and the piston rings can be renewed.

The intermediate central part could, of desired, be made as an integral piece and nevertheless be adapted for easy removal. In that case, all that would be required would be the lifting of the upper barrel part through a small distance to clear the way for the central part.

The expansion joints are located at places at which no excessive gas pressures can occur.

A packing in the form of a tube adapted to be expanded and cooled by water, or another liquid, under pressure is of considerable value in connection with a compound cylinder, the constituent parts of which have freedom of appreciable relative displacement, especially in view of the fact that said tube can easily be made so that it does not in the least impair the fitting and the removal of the intermediate part. If said tube is at the same time used for exerting permanent pressure on the packing material provided between the cylinder barrel parts adapted to slide along one another, perfect tightness of the joints is ensured.

What I claim is:—

1. In a double-acting two stroke engine, a frame, a composite cylinder comprising two end sections secured to said frame, a free intermediate section, expansion joints between said free intermediate section and said end sections, and positioning means for maintaining said sections in axial alignment, said intermediate section having scavenging and exhaust ports.

2. In combination with the structure claimed in claim 1, packing means between said intermediate section and said end sections.

3. In the combination claimed in claim 1, said intermediate section comprising two axially joined portions, one portion having the scavenging ports, the other the exhaust ports.

4. In combination with the structure claimed in claim 1, cooling means for each section.

In testimony whereof I affix my signature.

GERARD JOHAN LUGT.
